P. HEELY

TOOL FOR SPREADING TUBES OF WATER TUBE BOILERS

Filed April 18, 1922

Inventor
Patrick Heely
By his Attorney
J.B. McGivern.

UNITED STATES PATENT OFFICE.

PATRICK HEELY, OF BROOKLYN, NEW YORK.

TOOL FOR SPREADING TUBES OF WATER-TUBE BOILERS.

Application filed April 18, 1922. Serial No. 555,502.

To all whom it may concern:

Be it known that I, PATRICK HEELY, a citizen of the United States, residing at Brooklyn, in the county of Kings and State 5 of New York, have invented certain new and useful Improvements in a Tool for Spreading Tubes of Water-Tube Boilers, of which the following is a specification.

My invention relates to a tool that is used 10 for spreading tubes of water tube boilers and its main object is to provide an improved tool of this character by means of which tubes may be spread to the proper extent for the introduction or removal of fire-brick between the tubes thus spread. The 15 tool is particularly adapted for inserting between sets of tubes so as to spread them apart sufficiently for permitting the particular shaped fire brick to be properly 20 placed in position between the several rows of pipe or tubes in front of the baffle-plates.

As is well known, the tubes of the boiler 25 pass through baffle-plates which are protected from the direct action of the intense heat of the furnace by fire bricks of a very refractory material, these fire bricks being so shaped as to fill the spaces between the several tubes, and being generally identical in contour and construction to fill a substantially 30 diamond-shaped space between four adjacent water tubes and lying in close contact with adjacent fire bricks filling other similar spaces. In order to insert or remove a fire brick between the several sets 35 of tubes of the boiler, the herein described tool will readily spread the set of tubes a sufficient distance to enable a workman to insert a fire-brick in the shaped space, without in any way cutting or weakening such 40 fire-brick and without leaving an opening between adjacent fire-bricks. The fire-bricks are inserted into position by a special tool made for this purpose and which is used in connection with the spreader. Such tool 45 for applying the fire-brick into position forms another application.

The present invention is an improvement 50 upon that disclosed in a patent granted to me, No. 808,920 of January 2nd, 1906, and a patent of continuation granted December 20, 1910, No. 979,162, both of which disclose a spreading tool adapted to permit the spreading of water tubes of boilers at a suitable point in advance of the baffle plate, and particularly to a tool for both spreading 55 the tubes and holding them in their spread

positions while a fire-brick is being inserted or removed.

With these and other objects in view, the improvement consists in the construction, 60 combination and arrangement of parts, as will be hereinafter more fully described, illustrated in the accompanying drawing and pointed out in the claims.

My improvement will be more clearly understood by reference to said drawing which illustrates merely an example of means for putting my improvement into practice, and wherein;

Fig. 1 is an elevation, partly in section, 70 of a tube spreading tool, showing the several faces partly spread as they would be when inserted between tubes of the boiler;

Fig. 2 is an edge view looking from right to left;

Fig. 3 is a cross-section on the line 2—2 of Fig. 1 when the jaws are in their closed position; and

Fig. 4 is a detached detail of the floating 80 plunger.

The essential element of the spreader is the head. In this particular case, the head comprises three essential parts, first an outer and inner head that are telescopically assembled together, and having a spring element for holding the heads normally closed, which will be later explained. My improved form herein shown consists of a casting, the outer member 5 of which is provided with two side walls 6 and 7, and at the center is 90 provided with a reinforcement 8 and 9, extending the length of the head. The side walls 6 and 7 are reinforced by an operating face 10 and 11, which terminates in the reinforcement 8 and 9, and which together 95 with the other parts, forms a very strong single member of the head. To the inside of the reinforcement 8 and 9 are grooves 12 and 13, which extend from the top of the head to the lower part, as shown in Fig. 1. The side walls and operating faces 10 and 11 extend to the neck 14 where it bulges out in a union connection 15. The whole head thus far described consists of two spaced walls which terminate at such union. The latter 105 may be internally screw threaded at 16 and has a shoulder 17 provided at the upper end. A communicating passage 18 connects the upper space with the interior of the union.

The cooperating head member or inner 110 member 19 is also a casting and fits between the walls 6 and 7 and is slidably operated

therebetween. Said member 19 has an arm, the upper end of which carries on each side a reinforced rib 21 and 22 (Figure 3), which fits into grooves or ways 12 and 13, which 5 not only strengthens said member 19 where the greatest amount of strain is sustained by such a tool, but acts as a guide for said member when being raised or lowered. This second head has operating faces 23 and 24, 10 which extend out beyond the body portion of the head, and not only forms a good holding face for the tool against the tube, but presents when in its closed position, a practically smooth surface. The operating faces 15 23 and 24 are sustained by a web or brace 25 and 26 which with the ribs 21 and 22, provide a very desirable tool that may be relied upon to do the work for which it is designed with the reliability required. The 20 third important improvement of the head of my tube spreading tool as before noted, is the depending stem 27, carried by the inner head 19, said stem extending downwardly through the union connection 15 and 25 through gland or washer 27'. The lower end of said stem has a heavy spring 28 secured thereon, its upper end pressing against the gland or washer 27', and the other end against a washer 29, held in place 30 by a lock nut 30. Thus it will be seen that the power of the spring at all times will be such as to hold the two heads normally closed, thereby preventing the heads from being in any other than a closed position. 35 Secured to the union connection 15 is a tubular handle 31, which is seated in a terminal or block 32 within which is also housed a suitably threaded bolt 33, its outer extending end having a suitable head 34, 40 which may be provided with openings 35 for the insertion of means for turning it around, or it may be provided with outwardly extending fingers for the purpose. Either of these means are common expedients for 45 turning the screw manually. Intermediate between the end of the stem 27 and the bolt 33 is a floating plunger or free and unattached transmitting block 36, by means of which any pressure that may be exerted on 50 it by the screw 33 will force the stem 27 upward and thereby open the two heads, as shown in Fig. 1, and consequently if it were inserted between pipes or tube boilers, it 55 would necessarily separate them also, the bosses 20 and 21 acting as guides as the inner head moves upwardly.

In accordance with the provisions of the patent statutes, I have herein described the principle of my invention or improvement, 60 which I now consider to represent the best embodiment thereof, but I desire to have it understood, that the various forms mentioned are only illustrative and that the spreading tool can be designed in other ways 65 other than those described, but all are in-

tended to come within the scope of the claims. Also, while the general design of the head is about the same as in my previous patents, yet the same may undergo further changes, without in any way interfering 70 with the general operations or results for which the tool was designed.

What I claim is,

1. A tool for spreading tubes and the like, comprising outer and inner heads movable relatively and fitted telescopically together, a handle rigidly connected with one head, a rod on the other head projected slidably into the handle, resilient means within the handle acting on said rod to draw the heads together to a closed position, and means carried by the handle for forcing the heads apart to a desired degree. 75

2. A tool for spreading tubes and the like, comprising a handle, an outer head rigid with the handle and having side walls, an inner head telescopically received between said side walls and adapted to project beyond the side walls for engaging tubes, a rod connected to said inner head and slidably mounted through the handle, means in the handle acting against the handle and said rod to normally draw the inner head into the outer head, and means carried by the handle for forcing the inner head outwardly without regard to the action of said means. 85

3. A tool for spreading tubes and the like, comprising a handle, an outer head rigid with the handle and having substantially parallel spaced side walls, an inner head telescoping within the walls of the outer head, a rod carrying said inner head and being slidably mounted in the handle, means acting against said rod and the handle for drawing the inner head entirely home within the walls of the outer head, a screw mounted in the handle, and a floating member between said screw and the rod. 95

4. A tool for spreading tubes and the like, comprising an outer head having side walls with grooves therein, an inner head slideable and telescoping with respect to said outer head and having ribs for sliding in the grooves in said walls, a handle for carrying said heads, means for normally and yieldably drawing the heads together, and means carried by the handle for independently and adjustably moving the heads apart. 110

5. A tool for spreading tubes, comprising a tubular handle, an outer head secured removably to one end of said tubular handle, said head provided with inner working surfaces and with substantially parallel spaced walls projecting outwardly at substantially right angles from said working surfaces, said walls having grooves extending substantially co-axial with the handle, an inner head having ribs slidably received in the grooves, said inner head provided with webs adapted to be received between the walls of 125 130

the outer head, flanges at the outer sides of the webs affording an outer working surface and adapted to overlap the outer ends of said walls, a stem projecting inwardly from said inner head and slidably in the tubular handle, a coil spring wound about said stem for urging the inner head within said walls of the outer head, a tubular floating piston in said handle separate from said stem and adapted to abut thereagainst, and a screw 10 carried by the handle and engaging against the opposite end of said floating piston.

In testimony whereof I affix my signature.

PATRICK HEELY.
